UNITED STATES PATENT OFFICE.

JAMES HAROLD WALKER AND JAMES ALLISON OLINGER, OF WEST CHICAGO, ILLINOIS.

UNDERREAMER.

1,095,050.

Specification of Letters Patent. Patented Apr. 28, 1914.

Application filed November 9, 1912, Serial No. 730,465. Renewed March 4, 1914. Serial No. 822,475.

To all whom it may concern:

Be it known that we, JAMES H. WALKER and JAMES A. OLINGER, citizens of the United States, residing at West Chicago, in the county of DuPage and State of Illinois, have invented a new and useful Underreamer, of which the following is a specification.

This invention has reference to improvements in under reamers for well casings, and its object is to provide a tool of this character wherein the cutters shall be markedly firm in their seats while in action and at the same time will readily collapse for the introduction or withdrawal of the tool from the well casing, or partially collapsed during the retractive movement of the reamer, and furthermore present a construction particularly adapted for cheap production, the construction contributing both to facilitating the manufacture and the attainment of a rigid working condition wherein lost motion is practically eliminated.

The invention comprises certain improvements in the cutters with respect to those portions thereof which enter the cutter head, and also certain improvements in the seats into which the cutters are inserted, together with an improved key, which by its construction causes a firm seating of the cutters during the progress of the active stroke of the reamer.

The invention will be best understood from a consideration of the following detailed description, taken in connection with the accompanying drawings forming a part of this specification, with the further understanding that while the drawings show a practical form of the invention, it is susceptible of other practical embodiments, wherefore the invention is not limited to any strict conformity with the showing of the drawings, but may be changed and modified so long as such changes and modifications mark no material departure from the salient features of the invention.

In the drawings:—Figure 1 is an elevation of the reamer in the collapsed position ready for introduction into a well casing. Fig. 2 is a longitudinal diametric section with some parts in elevation showing the cutters of the reamer in the expanded position. Fig. 3 is a section on the line 3—3 of Fig. 2. Fig. 4 is a rear elevation of one of the cutters removed from the cutter head. Fig. 5 is a side elevation thereof. Fig. 6 is

a front elevation of the cutter. Fig. 7 is a section on the line 7—7 of Fig. 3 with the cutters omitted. Fig. 8 is a section on the line 8—8 of Fig. 3 with the cutters and other movable parts omitted. Fig. 9 is a perspective view of a key used in the reamer.

Referring to the drawings, there is shown an elongated stem 1 terminating at one end in a head 2 and at the other end provided with a screw nipple 3 for attachment to an operating rod or tube. The stem 1 and head 2 constitute the body portion of the cutter head, and this head carries oppositely disposed reaming cutters 4. Extending lengthwise of the head in the longitudinal axis thereof is a passage 5 of appropriate size to receive a rod 6 and a spring 7 surrounding the rod and at one end the passage 5 is contracted as indicated at 8 to form a shoulder 9 against which one end of the spring abuts, while the other end of the spring engages a washer 10 held to the corresponding part of the rod by a pin 11. The rod 6 is of sufficient length to extend into the contracted end 8 of the passage 5 and there the rod is provided with a transverse longitudinally elongated slot 12 through which there is extended a key 13 which may be in the form of an elongated flat plate of appropriate dimensions. This key has produced therein at about midway of the ends of one edge a notch 14 of a size to straddle the rod 6 where traversed by the slot 11, so that the key 13 is held against movement lengthwise of the key by engagement with that portion of the rod 6 which seats in the notch 14. That long edge of the key 13 remote from the edge provided with the notch 14 has oppositely disposed beveled walls 15 deepest at the inner ends and gradually rising to the outer ends of the key, there remaining a central portion 16 of the full width of the key, which central portion projects to substantially equal distances on the opposite sides of the rod 6 when the key is in place. The purpose of this key will appear hereinafter.

On diametrically opposite sides the head 2 has elongated recesses 17 formed therein, these recesses being of approximately equal diameter throughout their length for a portion of the depth from the outer face of the head inwardly and at the inner portions these recesses are widened out laterally into grooves 18 on opposite sides, which grooves are approximately triangular in cross section with the forward wall meeting the cor-

- responding wall of the recess 17 at an angle of substantially forty-five degrees, as best shown in Fig. 3. The outer angles of these grooves, that is, those angles which consider the two grooves of a recess 17 are the farthest separated, approach toward the stem of the head at a slight angle, say, of about two degrees. In Fig. 7 these approaching angular portions are indicated at 19, but for the purposes of illustration the angle of taper is somewhat exaggerated. Where each groove 18 meets the corresponding recess 17 the edge of junction indicated at 20 in Fig. 8 is of about six degrees inclination to the longitudinal center line of the head 2, being closer at the free end of the head 2 to the said longitudinal center line of the latter than toward the stem end of said head. Extending through the portion of the head 2 between the recesses 17 is a slot 21 to permit the passage of the key 13, and this slot is sufficiently elongated in the direction of the length of the head to provide for a considerable distance of travel 25 of the key lengthwise of the head, in which case the rod 6 participates in such travel and the spring 7 is contracted or expands in accordance with the direction of travel of the rod.
- 30 Each cutter 4 has a body portion 22 terminating in a cutting edge 23 appropriately curved on an arc corresponding to the outer curvature of the well casing and projecting from that end of the body portion 22 of the cutter remote from the edge 23 is a stem or tang 24. From the cutting edge 23 the cutter body 22 is beveled, as indicated at 25, and the body portion then widens and terminates in a flange 26 as wide as the body portion 22 and extending laterally thereof. The stem 24 has its outer face curved similarly to the curvature of the body portion 22 and meets the outer face of the body portion 22 at an obtuse angle.
- 45 At the sides of the stem 24 adjacent the flange 26 are beveled tongues 27 extending longitudinally of the stem 24 and projecting toward the sides of the body of the cutter, these beveled tongues having those faces 50 presented toward the front or rounded face of the cutter beveled at an angle of about forty-five degrees, and where the beveled faces meet the side faces of the stem, which side faces may be approximately parallel, the line of junction is at an angle of about six degrees to the plane of the outer face of the flange 26. Moreover, the corresponding face 28-29 of the stem 24 is at an angle to the plane of the said face of the flange 26 of about six degrees. The face 28-29, which may be termed the rear face of the stem 24, is cut back or recessed, as indicated at 30, to form a bevel shoulder 31 merging into the portion 28 of the rear face of the stem 24. Practiced through the stem 24 near that end remote from the body portion 22 is a slot 32 having one edge 33 beveled at about the angle of bevel of the edge 15 of the key 13.
- 55 The body portion 22 where joining the stem 24 is of greater lateral extent, thereby forming flat shoulders 34 and the free or upper end of the stem, indicated at 35, may be substantially parallel with the shoulders 34, while the beveled portion 33 of the slot 32 is presented toward the face 35 of the stem 24.
- 60 With respect to the various angles mentioned it may be stated that no strict conformity to these angles is necessary, but they are found to approach closely to desirable angles, and especially with respect to the angle of the engaging face of each tongue 27. An angle of about forty-five degrees is found to answer markedly well 65 for the purpose of holding the parts firmly against any lost motion and at the same time releasing freely without sticking.
- 65 When the tool is assembled, the cutters 4 are introduced into the head 2 from the end thereof remote from the stem 1, the tongues 27 taking into the grooves 18 until the free ends 35 of the stems 24 abut against those ends of the recesses 17 toward the stem 1, the other ends of these recesses being open. 70 The cutters 4 are held against more than a limited movement laterally with respect to the longitudinal center line of the stem 1 by the undercut grooves 18 in which the tongues 27 engage, but the cutters 4 may move lengthwise of the head 2. The rod 6 having been inserted with the spring 7, washer 10 and pin 11 already applied, the spring is forced along the stem 1 to compress the spring 7 and until the slot 12 is coincident with the slots 21 and with the slots 32 in the stems 24, when the key 13 may be introduced through one of the slots 32 and passed through the slot 12 until the notch 14 is in traversing relation to the slot 12 when on the release of the rod 6 that portion at one end of the slot 12 will enter the recess 14, and the beveled edges 15 of the key 13 will then engage the beveled portions 33 of the grooves 32 moving the stems of the cutters until the ends 35 of these stems are in engagement with the corresponding ends of the recesses 17. While the parts are in this position the portions 28 of the rear faces of the cutters are in engagement with the corresponding inner walls of the recesses 17, thus forcing the tongues 27 of the stems 24 into firm engagement with the beveled walls of the grooves 18. At the same time the inwardly directed beveled edges 15 engaging the correspondingly directed beveled edges 33 of the slots 32, cause the drawing of the corresponding ends of the cutters toward the outer line of the head 2 and holding them there. The cutters are now in the 80

expanded position with the cutting edges 23 adapted to engage the inner walls of the bore of the well, assuming that the under reamer is below the well casing, and enlarge 5 the bore to an extent permitting the lowering of the casing. Of course, in this condition of the parts the extent of separation of the cutting edges is greater than the internal diameter of the casing and consequently it 10 is necessary to contract the cutters to move them one toward the other to reduce the lateral extent of the reamer to permit it to move through the interior of the casing. To bring this about the cutters are moved 15 lengthwise of the head 2 in a direction away from the stem 1 and against the normal action of the spring 7. This movement is continued, the key 13 and rod 6 participating 20 therein, until the beveled shoulders 31 reach the then lower end of the head 2, whereupon the cutters may be made to approach one toward the other until the recessed portion 30 of the rear wall of each cutter engages the inner edge of a recess 17 25 at the then lower end of the head. When the reamer has been introduced into the casing and reaches the lower end thereof, the action of the spring 7 through the key 13 upon the cutters tends to move them toward the stem 1, this movement being permitted 30 by the beveled shoulders 31, whereupon the cutters move one away from the other until the shoulders escape from the lower face of the head, and then the reaction 35 of the spring 7 causes the cutters to move quickly along the head until the ends 35 engage the closed ends of the recesses 17, in which position a small portion of the end 35 projects beyond the outer wall of the head 2 constituting an exposed shoulder. 40 Now, when it is desired to withdraw the reamer from the well, the exposed portion of the ends 35 may be brought into engagement with the lower end of the casing, thus 45 causing the cutters to move lengthwise of the head 2 compressing the spring 7 until the shoulders 31 reach the lower ends of the recesses 17, the ends 35 of the stems 34 having in the meantime approached because of 50 the taper form of the grooves 18 lengthwise thereof, and then the ends 35 escape from engagement with the casing permitting the indrawing of the tool into the casing, and its ultimate extraction from the upper end of 55 the casing. The beveled portions of the key wherein the bevels deepen toward the center of the key, in coaction with the corresponding beveled slots 32 tend to draw those ends of the cutters remote from the cutting edges 60 toward each other and to hold such ends firmly in their seats against any liability of lost motion.

Corresponding to the taper of the edges 19 of the grooves 18 the sides of the tongues 65 27 also taper, as indicated at 19^a, 19^b, this

taper being about two degrees, although not necessarily confined thereto, and because of this taper the tongues of the cutters seat firmly in the grooves 18, thus eliminating all side motion. On the upward or inactive 70 stroke of the reamer there is frictional engagement of the upper outer faces of the cutters with the walls of the bore and consequently there is a drag on the cutters which will tend to move them against the action 75 of the spring 7. The six degree taper of the back face of the stems 24 permits the cutter points or cutting edges to approach slightly under the action of the frictional drag of the up stroke, so that the cutting edges are 80 saved from excessive wear due to frictional engagement and their life is materially prolonged.

The forty-five degree beveled tongue has the advantage over another form of tongue 85 in that it may be manufactured more cheaply, and is not so liable to break and, moreover, has an advantage over a greater or lesser bevel in not sticking. During the active movement of the reamer there is a 90 great pressure or pull against the body portion outwardly, and this would naturally cause the cutters to bind were it not for the bevel employed, which overcomes this tendency. The taper ends of the key with the 95 taper toward the center not only holds the cutters in close contact with the body or head 2 when they are in working position, but also draws them inwardly when the reamer starts on its downward or cutting 100 stroke and correspondingly forces or holds the cutting edges outwardly.

Beside the working advantages stated, the structure is particularly adapted to ease of manufacture and consequent cheapness 105 thereof.

By extending the spring through the stem of the body portion of the under reamer the head carrying the cutters or bits may be made correspondingly short and the spring 110 may be as long as necessary to insure its freedom from breakage, which is liable to occur with a shorter and more powerful spring.

What is claimed is:—

1. In an under reamer, a head or stock having recesses or seats, the lateral walls of each of which are provided at the inner ends with longitudinal angle grooves having the walls meeting said lateral walls at an angle 115 thereto of substantially forty-five degrees, and said grooves being also inclined with respect to the recesses, and cutters or bits movable lengthwise in said recesses and provided with stems or tangs having lateral 120 walls with substantially forty-five degree tongues having their outer margins converging toward the free ends of the tongues.

2. In an under reamer, a head or stock, and bits adapted thereto to enter the head 125

- or stock from one end thereof, said stock having recesses opening at the said end for receiving the bits and provided with oppositely disposed grooves inclined to approach from the entering end of each recess toward the other end thereof and also inclined outwardly from the entering end of the recess toward the other end thereof, and the bits being provided with tongues shaped in conformity with the inclined grooves.
3. An underreamer comprising a cutter or bit having a body portion and a stem or tang portion with the latter provided with laterally projecting longitudinal tongues at the sides with their outer edges approaching one toward the other as they recede from the body portion, and a head or stock having a receptacle for the stem or tang of the cutter shaped in conformity therewith.
4. An underreamer comprising a cutter or bit having a body portion and a stem or tang portion provided with laterally projecting longitudinal tongues at the sides having their outer edges approaching one toward the other as they recede from the body portion and also inclining toward the front portion of the cutter, and a head or stock provided with a receptacle for the stem or tang of the bit shaped in conformity therewith.
5. An underreamer comprising a bit having a body and a stem or tang, said stem or tang having side tongues converging toward the free end of the tang and the rear face of the tang inclining toward the free end, the degree of convergence of the side portions being less than the degree of inclination of the rear face, and a head or stock provided with a receptacle for the stem or tang conforming with the shape of the latter.
6. An under reamer having bits or cutters each with a stem portion provided on the side walls with laterally projecting tongues tapering one toward the other in the direction of the free end of the stem, and said stem also inclining on the rear face toward the free end, and a stock or head having recesses for receiving the stems of the cutters with laterally disposed grooves tapering one toward the other in conformity with the tongues of the cutter stems.
7. An under reamer having bits or cutters each with a stem portion provided on the
- side walls with laterally projecting tongues tapering one toward the other in the direction of the free end of the stem, said stem inclining on the rear face toward the free end, and a stock or head having recesses for receiving the stems of the cutters, each recess having laterally disposed grooves tapering in conformity with the tongues on the cutter stems, and said tongues and grooves having engaging faces beveled at substantially forty-five degrees to the sides of the stems of the cutters and the corresponding sides of the recesses.
8. In an under reamer, cutters or bits having stems with slots traversing them and each slot increasing in width along one edge from the inner face of the stem toward the outer face thereof, and a key adapted to the slots in the stems of the cutters and having its end portions widening along one edge from the central portion toward said ends in conformity with the slots through the stems of the cutters.
9. In an under reamer, a stock or head portion, a key adapted to traverse the stock or head portion and provided with end parts tapering toward the middle portion, and bits or cutters for the head portion having stems with slots therethrough expanding toward the outer portions of the stems and shaped to receive the tapered ends of the keys.
10. In an under reamer, a stock or head portion, a key adapted to traverse the stock or head portion and provided with end parts tapering toward the middle portion, and bits or cutters for the head portion having stems with slots therethrough expanding toward the outer portions of the stems and shaped to receive the tapered ends of the keys, the stock being provided with a or head portion and provided with end rod adapted to said passage with the key traversing the slot, and a spring in the passage in surrounding relation to the rod.
- In testimony, that we claim the foregoing as our own, we have hereto affixed our signatures in the presence of two witnesses.
